FIG. 3

FIG. 8

FIG. 4

FIG. 5

FIG. 6

FIG. 7

FIG. 1 is a top plan view of a food packaging tray or the like showing my new design; and

FIG. 2 is a side elevational view thereof.

FIG. 3 is a bottom plan view of the food packaging tray shown in FIG. 1.

FIGS. 4 and 5 are end elevational views thereof.

FIG. 6 is a cross-sectional view thereof taken on line 6-6 as shown in FIG. 1.

FIG. 7 is a cross-sectional view thereof taken on line 7-7 as shown in FIG. 1.

FIG. 8 is a top perspective view of a segment thereof. I claim:

The ornamental design for a food packaging tray or the like, substantially as shown and described.
